UNITED STATES PATENT OFFICE.

JOHN ALTON HARRISS, OF NEW YORK, N. Y.

VOUCHER-RECORD.

1,248,488.

Specification of Letters Patent.

Patented Dec. 4, 1917.

Application filed January 18, 1917. Serial No. 142,977.

To all whom it may concern:

Be it known that I, JOHN ALTON HARRISS, a citizen of the United States, residing at New York, county of New York, and State of New York, have invented a new and useful Improvement in Voucher-Records, of which the following is a specification.

This invention relates to an improvement in voucher records, such for instance as bank 10 or pay checks, notes, orders, memoranda, etc.

It is customary to mount bank checks and the like in book form, the checks to be torn from the book as they are used, the stubs remaining in the book. Heretofore, in so far 15 as I am aware, there has been no means provided in such cases for remounting the checks or other vouchers after use in juxtaposition with said stubs so that said vouchers and said stubs would be at all times accessible for 20 ready reference and comparison. It is the main object of the present invention to provide a voucher record having means for remounting the separated vouchers after use in juxtaposition with the stubs. Another 25 object is the provision of means for mounting the separated vouchers in a position separated from but in juxtaposition with the stubs to facilitate examination of either or both. Another object is the production 30 of a simple and inexpensive device of the general character above indicated which will be substantially as compact as the voucher records heretofore used, and which will require little change in such voucher records. 35 With these and other objects not specifically mentioned in view, the invention consists in certain constructions and combinations which will be hereinafter fully described and then specifically set forth in the claims 40 hereto appended.

In the accompanying drawings, which form a part of this specification and in which like characters of reference indicate the same or like parts, Figure 1 is a perspective view of a device constructed in accordance with the invention; Fig. 2 is a sectional view taken on the line 2-2 in Fig. 1, but upon an enlarged scale; Fig. 3 is a perspective view of the structure shown in Fig. 1, 45 showing the separated vouchers remounted in juxtaposition with the stubs yet separated one from another; Fig. 4 is a perspective view of a modification of the structure shown in Fig. 1, particularly adapted to handle

vouchers of the loose-leaf type; and Fig. 5 is a sectional view taken on the line 5-5 of Fig. 4, but upon an enlarged scale.

In carrying the invention into effect, there is provided a support, a series of leaves superposed in book form on said support each leaf being adapted to be separated into a voucher and a corresponding stub, means for holding the stubs together, and means for remounting the separated vouchers after use on the support in juxtaposition with said stubs. In the best constructions, there is provided a series of leaves superposed in book form each leaf being adapted to be separated into a plurality of vouchers and a plurality of corresponding stubs, means for holding the stubs together, and means for remounting the separated vouchers after use in stacks on the support separated one from another but in juxtaposition with said stubs. All of these means may vary in construction within wide limits. The device selected to illustrate the invention is but one of a number of possible concrete embodiments of the same. The invention therefore is not to be restricted to the precise details of the structure shown and described.

Referring to the drawings, 1 indicates a support united by means of a binding 2 to a cover 3. Mounted upon the support 1 is a series of leaves 4 superposed in book form, each leaf being adapted to be separated into a plurality of vouchers 5 and a plurality of corresponding stubs 6. Each leaf is perforated at 7 to facilitate separation by tearing of the vouchers from the book and stubs.

Provision is made for remounting the vouchers after use in stacks upon the support 1 in juxtaposition with the stubs and where, as in the device shown in Fig. 1, the leaves are separable into a plurality of vouchers, then the remounting means will be so located as to cause the separation of the vouchers when remounted one from another but still in juxtaposition with the corresponding stubs. With this end in view, each of the vouchers is provided with a pair of holes 8 and these holes are adapted to be engaged by flexible metallic prongs 9. One end of each of these prongs is clamped, by means of a metal eyelet 10, to the support 1. In the record as made up; that is to say, before the vouchers are used, these prongs 9 lie flat upon the upper surface of the support

1, as clearly shown in Fig. 1 and in the left in Fig. 2. After the vouchers have been used and it is desired to remount them on the support 1, the prongs 9 are bent upwardly at right angles to the plane of the support 1 and passed through the holes 8 of the proper series of vouchers. The projecting ends are then bent downwardly over a thin binding bar 11, in each case, to hold 10 the series of vouchers firmly in position. This position is clearly shown in Fig. 3, and by an inspection of this figure, it will be readily seen that the vouchers are separated one from another but still mounted in juxtaposition with the corresponding stubs so that either series may be examined without disturbing and without interference by the other series.

In the modification shown in Figs. 4 and 20 5, which has the same purpose as the device shown in Figs. 1 to 3 inclusive but which is adapted to handle leaves in loose-leaf form, there is provided a support 12 and a cover 13 which are held together by means of a 25 series of bolts 14 passing through suitable apertures in the leaves. The vouchers marked 15 after use are held in remounted position upon the support 12 by means of similar bolts 16.

30 The structure shown in Figs. 4 and 5 is particularly useful in connection with very heavy voucher records in which the flexible prongs 9 might not have sufficient strength to hold the vouchers firmly in position.

35 In view of the foregoing, a detailed description of the operation of the invention is deemed unnecessary and is therefore omitted in the interest of brevity.

What is claimed is:

40 1. In a voucher record, the combination with a support, of a series of leaves superposed in book form on said support each leaf being adapted to be separated into a voucher and a corresponding stub, means for holding 45 the stubs together, and means independent of the stubs and holding means for remounting the separated vouchers after use on the support in juxtaposition with said stubs.

2. In a voucher record, the combination 50 with a flat rigid support, of a series of leaves superposed in book form on said support each leaf being adapted to be separated into a voucher and a corresponding stub, means for holding the stubs together, and means independent of the stubs and holding means for remounting the separated vouchers after use on the support in juxtaposition with said stubs.

3. In a voucher record, the combination 55 with a support, of a series of leaves superposed in book form on said support each leaf being adapted to be separated into a voucher and a corresponding stub, a binder attached to said support for holding the stubs together, and means independent of the stubs

and holding means for remounting the separated vouchers after use on the support in juxtaposition with said stubs.

4. In a voucher record, the combination 70 with a support, of a series of leaves superposed in book form on said support each leaf being adapted to be separated into a voucher and a corresponding stub, means for holding the stubs together, and means independent of the stubs and holding means carried by 75 said support for remounting the separated vouchers after use on the support in juxtaposition with said stubs.

5. In a voucher record, the combination 80 with a support, of a series of leaves superposed in book form on said support each leaf being adapted to be separated into a voucher and a corresponding stub, means for holding the stubs together, and flexible means independent of the stubs and holding means carried by 85 said support for remounting the separated vouchers after use on the support in juxtaposition with said stubs.

6. In a voucher record, the combination 90 with a support, of a series of leaves superposed in book form on said support each leaf being adapted to be separated into a voucher and a corresponding stub, means for holding the stubs together, and means independent of the stubs and holding means carried by 95 said support and located for remounting the separated vouchers after use on the support in juxtaposition with said stubs but slightly separated therefrom.

7. In a voucher record, the combination 100 with a support, of a series of leaves superposed in book form on said support each leaf being perforated to adapt it for separation by tearing into a voucher and a corresponding stub, means for holding the 105 stubs together, and means independent of the stubs and holding means for remounting the separated vouchers after use on the support in juxtaposition with said stubs.

8. In a voucher record, the combination 110 with a support, of a series of leaves superposed in book form on said support each leaf being adapted to be separated into a voucher and a corresponding stub the vouchers having holes punched therein, 115 means for holding the stubs together, and means independent of the stubs and holding means adapted to engage the holes of the vouchers for remounting the same after use on the support in juxtaposition with 120 said stubs.

9. In a voucher record, the combination 125 with a support, of a series of leaves superposed in book form on said support each leaf being adapted to be separated into a voucher and a corresponding stub the vouchers having holes punched therein, means for holding the stubs together, and flexible prongs independent of the stubs and holding means carried by 130 said support and

adapted to engage the holes of the vouchers for remounting the same after use on the support in juxtaposition with said stubs.

10. In a voucher record, the combination with a support, of a series of leaves superposed in book form on said support each leaf being adapted to be separated into a plurality of vouchers and a plurality of corresponding stubs, means for holding the stubs together, and means for remounting the separated vouchers after use in stacks on the support separated one from another but in juxtaposition with said stubs.

11. In a voucher record, the combination with a flat rigid support, of a series of leaves superposed in book form on said support each leaf being adapted to be separated into a plurality of vouchers and a plurality of corresponding stubs, means for holding the stubs together, and means for remounting the separated vouchers after use in stacks on the support separated one from another but in juxtaposition with said stubs.

12. In a voucher record, the combination with a support, of a series of leaves superposed in book form on said support each leaf being adapted to be separated into a plurality of vouchers and a plurality of corresponding stubs, a binder attached to said support for holding the stubs together, and means for remounting the separated vouchers after use in stacks on the support separated one from another but in juxtaposition with said stubs.

13. In a voucher record, the combination with a support, of a series of leaves superposed in book form on said support each leaf being adapted to be separated into a plurality of vouchers and a plurality of corresponding stubs, means for holding the stubs together, and means carried by said support for remounting the separated vouchers after use in stacks on the support separated one from another but in juxtaposition with said stubs.

14. In a voucher record, the combination with a support, of a series of leaves superposed in book form on said support each

leaf being adapted to be separated into a plurality of vouchers and a plurality of corresponding stubs, means for holding the stubs together, and flexible means carried by said support for remounting the separated vouchers after use in stacks on the support separated one from another but in juxtaposition with said stubs.

15. In a voucher record, the combination with a support, of a series of leaves superposed in book form on said support each leaf being perforated to adapt it for separation by tearing into a plurality of vouchers and a plurality of corresponding stubs, means for holding the stubs together, and means for remounting the separated vouchers after use in stacks on the support separated one from another but in juxtaposition with said stubs.

16. In a voucher record, the combination with a support, of a series of leaves superposed in book form on said support each leaf being adapted to be separated into a plurality of vouchers and a plurality of corresponding stubs the vouchers having holes punched therein, means for holding the stubs together, and means adapted to engage the holes of the vouchers for remounting the same after use in stacks on the support separated one from another but in juxtaposition with said stubs.

17. In a voucher record, the combination with a support, of a series of leaves superposed in book form on said support each leaf being adapted to be separated into a plurality of vouchers and a plurality of corresponding stubs the vouchers having holes punched therein, means for holding the stubs together, and flexible prongs carried by said support and adapted to engage the holes of the vouchers for remounting the same after use in stacks on the support separated one from another but in juxtaposition with said stubs.

In testimony whereof, I have signed my name to this specification.

JOHN ALTON HARRISS
